ATTORNEY

UNITED STATES PATENT OFFICE.

WILLIAM I. ZIDELL, OF LOS ANGELES, CALIFORNIA.

DESIGN FOR CHILDREN'S ROMPERS.

52,720.

Specification for Design. Patented Nov. 19, 1918.

Application filed August 12, 1918. Serial No. 249,586. Term of patent 7 years.

To all whom it may concern:

Be it known that I, WILLIAM I. ZIDELL, a citizen of the United States, residing at Los Angeles, in the county of Los Angeles and State of California, have invented a new, original and ornamental Design for Children's Rompers, of which the following is a specification, reference being had to the accompanying drawing, forming part thereof.

Figure 1 is a front view of my new design. Fig. 2 is a rear view of my new design.

I claim:

The ornamental design for children's rompers, as shown.

WILLIAM I. ZIDELL.

Witnesses:

W.M. M. RHEEM,
MARION KEMBLE.
